UNITED STATES PATENT OFFICE.

GUSTAV E. SCHNEIDER AND ROBERT W. DAILEY, OF CHICAGO, ILLINOIS.

DESIGN FOR A COMBINED SMOKER'S STAND AND SET.

Application filed July 26, 1928. Serial No. 27,592. Term of patent 3½ years.

To all whom it may concern:

Be it known that we, GUSTAV E. SCHNEIDER and ROBERT W. DAILEY, citizens of the United States, both residing at Chicago, in the county of Cook and State of Illinois, have invented a certain new, original, and ornamental Design for a Combined Smoker's Stand and Set, of which the following is a specification, reference being had to the accompanying drawing, forming a part thereof.

The figure is a perspective view of a smoker's stand showing our new design.

We claim:

The ornamental design for a combined smoker's stand and set, as shown.

Signed at Chicago, county of Cook, State of Illinois this 30th day of June, A. D. 1928.

ROBERT W. DAILEY.
GUSTAV E. SCHNEIDER.
